MACHINE FOR CEMENT COATING PLATFORM SOLES AND COVERS THEREFOR

Walter W. Prue, Auburn, Maine, assignor to
United Shoe Machinery Corporation, Flemington, N. J., a corporation of New Jersey

Application July 10, 1945, Serial No. 604,259

12 Claims. (Cl. 12—1)

1

This invention relates to coating platform soles and covers therefor and is herein embodied in a machine for applying adhesive used for securing the cover to the sole in the so-called "cover-lasting" operation.

In the manufacture of large quantities of shoes having yieldable platform soles the edges of which must be provided with a cover, it has been found convenient by many manufacturers to secure a strip of flexible material to the upper of the shoe, as by stitching, prior to the lasting operation. The strip is then provided with a coat of adhesive, hereinafter called "cement," and, after having been drawn taut around the periphery of the sole, is lasted over the margin thereof and held in place by the adhesive on the cover, usually in coaction with another band of adhesive on the sole. In a large proportion of such shoes, the cover material is not only flexible but frequently is flimsy and wrinkled, thus making it difficult to apply cement to it and especially to limit the band of cement to such a width that there will be little danger of the accidental sticking of the cover to the edge of the sole before the cover-lasting operation. For a similar reason, it is desired to have the band of cement on the platform sole spaced from the periphery thereof by a clean margin.

One object of the invention is to provide an improved machine for simultaneously coating such platform covers and the margins of the associated platform soles.

Still another object of the invention is to provide improved means for coating and tensioning the cover to remove the wrinkles and to facilitate the location of the band of coating material on the cover.

In accordance with one feature of the invention, a combined tensioning and coating roll is employed, engaging the inner surface of a cover already attached to the shoe. As illustrated, this roll is mounted for free rotation by frictional engagement with the cover and is supported upon an axis which is inclined downwardly and forwardly with respect to the direction of movement of the work. Cement is supplied to the periphery of the roll for transfer to the cover.

Another feature of the invention lies in the provision of a cover-supporting roll extending the whole height of the cover when the shoe is held in inverted position. This roll is positioned opposite to the combined tensioning and coating roll and, by reason of its heightwise extent, it serves both to support the cover in contact with that roll and to press against the work.

2

opposite the periphery of the platform sole, thereby effectively to feed the shoe so as to present the whole periphery thereof to the coating apparatus.

5 These and other features of the invention will best be understood from a consideration of the following specification taken in connection with the accompanying drawings, in which

10 Fig. 1 is a front elevation of the work-engaging parts of the machine, and

Fig. 2 is a side elevation thereof, showing a piece of work in position for treatment by the machine.

15 The invention is illustrated as embodied in a bottom-cementing machine of the type shown in Letters Patent of the United States No. 2,177,666, granted October 31, 1939, upon the application of Wilbur L. MacKenzie et al., to which reference may be had for description of those parts of the

20 machine not herein fully shown. The patented machine was designed for coating the bottoms of shoes which are held in inverted position and presented to a depending flexible nozzle, such as that shown at 10. This nozzle is supported upon a stud 12 carried on the frame 14 and is supplied with coating material under pressure from a can

25 15 through connections, such as the pipe fitting 16, containing a shut-off valve 18 which is arranged to be rotated under the control of the operator by a rod 20 connected to the valve through a universal joint 22.

30 The pipe fitting 16 is connected to a nozzle block 24 releasably supported upon a bracket 26 attached to the stud 12 and the nozzle block is held in position on the bracket by means of a latch 28. On the nozzle block are pivoted fingers 30 which swing on a pivot rod 32 and are urged downwardly to the position shown in Fig. 1 by means of a series of spring wires 34 carried, as in the patented construction, by a plate 36. The delivery of cement to the outlet openings 38 of the yieldably mounted fingers 30 is effected by means of a series of small tubes 40 the lower ends of which are slidably inserted in passages, in the fingers, leading to the outlet openings. These tubes are carried by a plate 42 and communicate with a recess 44 therein which is supplied from the pipe fitting 16 through a passage 46 in the block 24. A curved pipe 48, terminating above the fingers, is arranged to deliver drops of solvent thereto from a suitable source of supply so as to keep the fingers pivoting freely as they coat a sole moved from right to left in Fig. 1.

35 40 45 50 55 Supported just forward of the yieldable nozzle 10 is a combined cover tensioning and coating

roll 50. This roll is provided with vertical flutes and is mounted on a stud 52 which is threaded in a carrier 54 having a threaded stem 55 supported by a bracket 56 which for convenience is an extension of the spring-carrying plate 36. The carrier 54 is adjustable heightwise of the bracket 56 and transversely of the work path in a horizontal slot 57 therein, and is held in adjusted position by a threaded collar 58 and a lock nut 60. Cement is delivered to the periphery of this roll by means of tubes 62 supported in and supplied from the recess 44 in the same plate 42 which carries the tubes 40 for the yieldable nozzle 10. It will be noted that the axis of rotation of the fluted tensioning and coating roll 50 extends downwardly and forwardly with respect to the direction of movement of work carried from right to left in Fig. 1. By reason of this inclined relation, any point on the surface of the roll 50 moves not in a horizontal path but upwardly and to the left in Fig. 1. Thus, as it applies its coating to the cover material, the roll also draws the cover upwardly away from the platform sole and thus tensions the cover to remove wrinkles and to draw it to the height which it will assume when lasted over the sole. By reason of this tensioning effect, the location, with respect to the sole, of the band of cement on the cover can be definitely predetermined and spaced from the corner of the platform sole by such a clean margin that there will be little danger that the released cover will drop back to a position where the band of cement on it will accidentally stick the cover to the periphery of the platform sole.

Like the patented machine, the one herein illustrated is provided with a feed roll 64, of yieldable material such as rubber, which is attached to a driven shaft 66 passing through a movable carrier 68. When work is presented to the machine, the operator depresses a treadle which moves the carrier 68 out to the position shown in Fig. 2 where a portion of the carrier contacts a rigidly mounted stop 70 and thus determines the outward position of the feed roll 64. The feed roll shown here is, however, of different size and shape from that found in the patent and has a frusto-conical work-engaging surface 72 which extends heightwise far enough to engage and support the whole width or heightwise extent of a platform cover 74 secured to the upper 76 of a shoe on a last 78 and provided with a yieldable platform sole 80. The feed roll is positioned for engagement with the outside of the platform cover 74 substantially opposite to the roll 50 so that the cover is gripped between the two and, as the shoe is moved from right to left (Fig. 1) by the feed roll driven in the direction shown by the arrow, the fluted roll 50 is also turned, by frictional engagement with the cover, and effects both the coating of the inner surface of the cover and a tensioning thereof, as described above. At the same time, a band of coating material will be applied by the nozzle 10 to the margin of the platform sole 80 in a position spaced from the periphery thereof, as indicated in Fig. 2, so that a clean margin will be left adjacent to the periphery. The width of this clean margin may be determined by adjustment of the roll carrier 54 transversely of the bracket 56 along the slot 57, thereby to vary the relation between the roll and the nozzle and hence between the feed roll 64 and the nozzle. This locates the edge of the sole with respect to the nozzle.

Having thus described my invention, what I

claim as new and desire to secure by Letters Patent of the United States is:

1. In a machine for coating platform covers attached to shoes, cover-supporting and work-feeding means, and a combined coating and tensioning device operating upon the inner surface of the cover.
2. In a machine for coating platform covers attached to shoes, cover-supporting and work-feeding means, a combined coating and tensioning device operating upon the inner surface of a cover supported by said means, said device comprising a roll inclined with respect to the path of movement of the shoe, and means for supplying coating material to the periphery of said roll.
3. In a machine for coating platform covers attached to shoes, cover-supporting and work-feeding means, a combined coating and tensioning device operating upon the inner surface of the cover, said latter device comprising a freely rotatable roll inclined with respect to the path of movement of the shoe, and means for supplying coating material to the periphery of said roll.
4. In a machine for coating platform covers attached to shoes, a combined coating and tensioning device, and a combined work-feeding and cover-supporting means coating with the tensioning device and driven to enable the operator to present successive portions of the margin of the cover to said coating device.
5. In a machine for coating platform soles and platform covers attached to shoes, a combined work-feeding and cover-supporting means, a combined cover-coating and tensioning device coating with the feeding and supporting means, said feeding and supporting means being driven to enable the operator to present successive portions of the margin of the cover to said coating means, and a yieldable nozzle positioned to apply a band of coating material to the margin of the platform sole.
6. In a machine for coating platform covers, a driven feed roll supporting the outer face of the cover and engaging the shoe to assist the operator in presenting successive parts of the periphery of the shoe to the machine, a cover-tensioning roll engaging the inside of the cover opposite to the feed roll, and means for supplying coating material to said tensioning roll, the coaction of said tensioning roll with the cover-supporting feed roll being effective to cause rotation of the tensioning roll.
7. In a machine for coating progressively the inner margins of platform covers attached to shoes having platform soles, driven work-feeding means supporting the cover and positioned to engage the outer surface of the cover adjacent to the periphery of the platform, a cover-tensioning roll opposite to said feeding means positioned upon an axis inclined downwardly and forwardly with respect to the direction of movement of the work, and means for supplying coating material to said roll.
8. In a combined platform sole and platform cover coating machine, a nozzle having a series of yieldable fingers, means for supplying cement to said nozzle to coat the margin of the platform sole, work-feeding means positioned to support the platform cover, a fluted roll against which the cover is pressed by said feed means, said fluted roll being mounted on an axis inclined downwardly and forwardly with respect to the direction of movement of the work, and a tube leading from the source of supply for the

articulated nozzle to the periphery of said inclined roll.

9. In a machine for simultaneously applying coatings to a platform sole and to an associated platform cover, means for supplying coating material, a yieldable nozzle for coating the platform sole, a roll for coating the platform cover, connections embodying a shut-off valve common to both coating devices between the supplying means and said coating devices, and means for feeding the work.

10. In a machine for coating platform covers on shoes having platform soles, a cover-coating roll inclined with respect to the bottom of the sole, and a driven feed roll supporting the outer face of the cover and engaging the full width thereof substantially opposite the cover-coating roll, said feed roll pressing the cover against the periphery of the platform sole to make the roll more effective in assisting the operator to present successive parts of the periphery of the shoe to the machine.

11. In a machine for coating platform covers attached to shoes, rolls arranged at opposite sides of and gripping the cover, means for driving one roll to feed the shoe, one of said rolls being mounted on an axis inclined downwardly with respect to the bottom of the shoe and forwardly

in the direction of feeding movement, thereby to cause a tensioning of the cover, and means to deliver cement to one of the rolls.

12. In a machine for simultaneously coating the margin of the bottom of a shoe and a projecting flexible cover adapted to be lasted over the bottom of the shoe, coating adjacent coating devices for applying cement to the flexible cover material and to the margin of the bottom of the shoe, means cooperating with one of said coating devices arranged to feed the flexible material, and means for causing the latter coating device to tension the material laterally of the feed movement as the material is coated.
